UNITED STATES PATENT OFFICE.

EUGENE MCKENNA, OF BRACKENRIDGE, PENNSYLVANIA.

ROTARY CARRIER.

1,099,186.

Specification of Letters Patent.

Patented June 9, 1914.

Application filed November 28, 1913. Serial No. 803,586.

To all whom it may concern:

Be it known that I, EUGENE MCKENNA, a subject of the King of Sweden, residing at Brackenridge, in the county of Allegheny and State of Pennsylvania, have invented certain new and useful Improvements in Rotary Carriers, of which the following is a specification.

The present invention relates to improvements in rotary carriers, and is designed especially for use in connection with metal rolling-mills, as for instance a mill for rolling sheet steel.

In the present practice, which is almost universal, the plates or sheets of steel as they emerge from the rollers of the mill, are manually conveyed, or assisted in their conveyance, to the table upon which they are to be stacked, or upon which they are to be detained until a further step in their treatment is to be taken.

The primary object of my invention is the provision of an instrumentality by means of which the sheets or plates of steel or other metal may be supported as they emerge from the rolls of the mill and carried to a suitable location. This purpose I accomplish by means of a rotary electro-magnet which is located in juxtaposition to the mill and is adapted to attract the steel plate and hold it suspended and simultaneously carry it to its place of deposit.

In the accompanying drawings I have illustrated one complete example of the physical embodiment of my invention constructed according to the best mode I have thus far devised for the practical application of the principles of my invention. Although I have illustrated a mill of the two-roll type, it will be readily understood that I may use the carrier in combination with other forms of mills, as for instance mills employing three rolls, where the rolled plate is returned through the two upper rolls after passing through the two lower ones, and it will be evident that my conveyer or carrier is equally applicable here, as in other forms of mills.

Figure 1 is a side elevation of so much of a sheet-metal rolling mill as is necessary to illustrate the application thereto of my invention, the novel form of carrier being shown in operative position with relation to the mill. Fig. 2 is a plan view of a fragment of the rotary carrier or electro-magnet, showing the poles or contact members of the

magnet. Fig. 3 is an end view of a portion of the magnet showing the connection of wires to the magnet poles or cores. Fig. 4 is a fragmentary sectional view of a drum forming part of the magnet upon which the poles or contact members of the magnet are carried. Fig. 5 is a plan view of Fig. 1. Fig. 6 is an enlarged fragmentary top plan view showing the bearing for the shaft of the magnet, a segmental disk, a collector disk, the brushes, etc., for the supply of electricity to the magnet. Fig. 7 is an end view of Fig. 6 showing the shaft in section.

The rolling mill in connection with which I have illustrated my invention, is of a well known type and comprises the upper power roll 1, the lower roll 2, and the housing 3 in which the rolls are adapted to revolve as usual. The metallic sheet is fed through the rolls from left to right in Fig. 1, and Fig. 1 illustrates the purpose of my rotary carrier, wherein it will be seen that the forward end of the sheet which has passed through the rollers or rolls is held elevated from the table 4.

The rotary carrier I have designated by the numeral 5 as a whole, and this carrier is supported by means of its shaft or axle 6 from the standards 7, 7 which are secured at their lower ends to the mill housings as seen at 8, Fig. 1. Journal bearings 9, 9 are provided at the upper ends of the standards in which the shaft 6 may be revolved, and the shaft is revolved from the power roll 1 by means of a pair of sprockets 10, 11, and chain 12. The carrier includes a metallic drum 13 fixed on the shaft 6, and this drum is covered on its periphery with a plurality of magnetic poles, arranged in longitudinally aligned series, four being illustrated in the drawings (Fig. 5). Each of these magnetic poles comprises a core 14, preferably of soft iron, securely held to the drum by means of bolts or screws 15, 15, and the cores are wire-wound as indicated at 16, in Figs. 4 and 5. Each aligned series of poles is insulated from the other series and from the drum by proper insulating material, and each pole of each series is provided with the usual wires 17 and 18, the former connected to a collector disk 19, and the latter, each connected to a separate and independent segment 20 of a segmental disk 21. These two disks 19 and 21 are fixed to and revolve with the shaft 6 of the carrier, and it will be seen in Fig. 3, espe-

cially, that all the collector wires 17 are connected at the point 22 and then led as a single cable to the collector disk 19, while the wires 18 are extended from a segment 5 20 to the nearest core on the periphery of the drum.

Each disk 19 and 21 is provided with a brush, as 23 and 24 respectively, the former carried by the holder 25 and the latter by 10 its holder 26, the usual springs 27 being employed to hold the brushes in contact with the disks. The feed and return wires for the brushes are indicated at 28 and 29 in Fig. 6, and the necessary insulation is indicated at 30 in Fig. 7. The circuit for each pole is thus completed through feed wire 28 from the dynamo, brush 23, disk 19, through cable 17' to point 22 thence through a wire 17, soil 16, wire 18, segment 20, brush 24, 15 outlet wire 29 to the dynamo. One row of poles (comprising four contact points) may be magnetized or a greater number of rows may be magnetized as desired, and this difference may be provided for by increasing 20 the area of the brush 24 so that it will contact with more than one segment 20. Thus if the brush is in contact with only one segment, only one row of coils will be energized, while if a greater number of segments 25 are in contact with the brush, a corresponding number of rows will be energized.

The operation of the apparatus is manifest in Fig. 1 wherein a sheet 32 is shown as emerging from the rolls of the mill, but is held suspended as it progresses therefrom, by the rotary carrier 5 whose energized 30 poles are holding the metal in the air. It

will be understood that only the lowermost row of poles is magnetized or energized at one time, but the lowermost row is of course continually changing as the carrier is revolved from the power roll. As the carrier 5 revolves with the rolls the metallic sheet or plate is supported and guided to position until it is deposited on the table 45 as will be understood.

While I have heretofore, and in the claims will hereinafter refer to a sheet or plate, it will of course be understood that other forms or shapes of articles may be used. 50

Having thus fully described my invention, what I claim as new and desire to secure by Letters Patent is:—

1. The combination with a mill as described, of a rotary electro-magnetic carrier 55 adapted to support a moving sheet, and means to rotate the carrier simultaneously with the operation of the mill.
2. The combination with a mill including a driving roll, of a rotary electro-magnetic 60 carrier, and means actuated by said roll to operate the carrier.
3. The combination with a mill including a driving roll, of a rotary electro-magnetic 65 carrier, a sprocket wheel on the roll, a second sprocket on the carrier, and a chain connecting said sprockets.

In testimony whereof I affix my signature in presence of two witnesses.

EUGENE McKENNA.
